Des. 230,527
Patented Feb. 26, 1974

230,527

TAPE CASSETTE CABINET

Joseph L. Berkman, 17 Brewster Terrace,
New Rochelle, N.Y. 10804

Filed Feb. 7, 1972, Ser. No. 224,400

Term of patent 14 years

Int. Cl. D3—02

U.S. Cl. D87—1 D

FIG. 1

FIG.2

FIG.3

FIG. 4

FIG. 5

FIG. 1 is a perspective view of a tape cassette cabinet showing my new design with the lid in open position; FIG. 2 is a top plan view with the lid in closed position; FIG. 3 is a front elevational view thereof; FIG. 4 is a rear elevational view thereof; and FIG. 5 is a side elevational view thereof.
I claim:
The ornamental design for a tape cassette cabinet, as shown.

UNITED STATES PATENT OFFICE
CERTIFICATE OF CORRECTION

Patent No. Des. No. 230,527   Dated February 26, 1974

Inventor(s) Joseph L. Berkman

It is certified that error appears in the above-identified patent and that said Letters Patent are hereby corrected as shown below:

The title of invention should read

-- TAPE CARTRIDGE CABINET --; in the description of Fig. 1, and in the claim, "tape cassette cabinet", each occurrence, should read -- tape cartridge cabinet --.

Signed and sealed this 24th day of September 1974.

(SEAL)
